UNITED STATES PATENT OFFICE.

FRANK KUHN, OF DETROIT, MICHIGAN.

ELECTRIC VAPORIZER.

1,125,028.

Specification of Letters Patent.

Patented Jan. 12, 1915.

Application filed April 5, 1912. Serial No. 688,604.

To all whom it may concern:

Be it known that I, FRANK KUHN, a citizen of the United States of America, residing at Detroit, in the county of Wayne and 5 State of Michigan, have invented certain new and useful Improvements in Electric Vaporizers, of which the following is a specification, reference being had therein to the accompanying drawings.

10 The invention relates to vaporizers and more particularly to carbureters for explosion engines.

It is the object of the invention to provide an electric heater or vaporizer which 15 is readily attachable to any of the usual constructions of carbureters or induction conduits for explosion engines and which in itself is a simple and inexpensive construction to manufacture.

20 To this end the invention consists in the construction as hereinafter set forth.

In the drawings,—Figure 1 is a longitudinal section through the induction conduit of an explosion engine to which my 25 attachment is applied; Fig. 2 is a perspective view of the attachment; Fig. 3 is a cross section in a plane transverse to Fig. 1; Fig. 4 is a sectional view similar to Fig. 1 showing a modified construction.

30 With explosion engines which employ liquid fuel such as gasoline, it is usual to form the carbureter as a separate unit which is attached to the induction conduit of the engine. The attachment is most generally by a flange union, the abutting flanges being bolted together with a suitable gasket therebetween. It is desirable in cold weather to assist the vaporization of the oil by preheating, and on account of its 35 instantaneous action, an electric heater is peculiarly adapted for this purpose.

40 My improvement consists in the arrangement of an electric heater in a member which is insertible in the induction conduit 45 and more particularly in an insulator member to which the naked resistor may be attached.

As shown in Figs. 1, 2 and 3, A is the flange end of the induction conduit of an 45 explosion engine and B the correspondingly flanged portion of the carbureter attached to said conduit. C is a member formed of

insulating material having an aperture D corresponding to the interior dimension of the conduit A and having its outer contour 55 preferably corresponding to that of the flanges on the members A and B. Thus the member C may be inserted between said flanges and when clamped in position will operate as a gasket. D' is the electric resistor which may be a coil of wire or of any other desired shape. The terminal connections E for this resistor pass out through the side of the member C, and as shown in Figs. 2 and 3, these consist of threaded 60 studs having the clamping nuts F, F' for attachment to the resistor and external circuit.

In Fig. 4 a modified construction is shown in which a screw-threaded plug G of insulating material is detachably inserted into a correspondingly threaded aperture in the wall H of the induction conduit. I are terminal connections passing through said plug and J is a resistor attached to the 70 inner ends of these terminals.

With both constructions, the heater may be readily inserted or removed from the conduit so as to permit of repair or replacement, and in each case the construction is 80 exceedingly simple and inexpensive to manufacture.

What I claim as my invention is:

1. The combination with an induction conduit having abutting sections, of a comparatively thin open-centered member arranged between the abutting sections, an electric resistor carried by said member, and a terminal connection passing out through said member. 90

2. The combination with an induction conduit having abutting sections, of a comparatively thin open-centered gasket formed of insulating material, an electric resistor arranged within the open center of said 95 gasket, and a terminal connection attached to said resistor and passing out through the gasket.

3. The combination with an induction conduit having abutting flange sections and 100 clamping means for securing said sections together, of a comparatively thin open-centered gasket formed of insulating material, an electric resistor comprising a coil of wire

arranged within the open center of said gasket, and terminal connections passing out through said gasket, the inner ends of said terminals projecting within the open center of the gasket and being respectively connected to the ends of said wire.

In testimony whereof I affix my signature in presence of two witnesses.

FRANK KUHN.

Witnesses:

W. J. BELKNAP,
JAMES P. BARRY.
